UNITED STATES PATENT OFFICE

EDWIN F. M. SPEIDEL, OF EDGEWOOD, RHODE ISLAND

DESIGN FOR A BRACELET CHAIN

Application filed August 13, 1931. Serial No. 40,842. Term of patent 3½ years.

To all whom it may concern:

Be it known that I, EDWIN F. M. SPEIDEL, a citizen of the United States of America, residing in Edgewood, county of Providence, State of Rhode Island, have invented a new, original, and ornamental Design for a Bracelet Chain, of which the following is a specification, reference being had to the accompanying drawings forming a part thereof.

Fig. 1 is a top plan view; Fig. 2 is a section on line 2—2; and Fig. 3 is a section on line 3—3 of Fig. 1, of a bracelet chain, showing my new design with the essential feature of the design in full lines and the non-essential portion of the chain in dotted lines in Fig. 1.

The essential feature consists in the appearance at the end of each of the links of the bracelet of a portion of two interwoven links on the face but with a smooth back.

I claim:

The ornamental design for a bracelet chain, substantially as shown and described.

EDWIN F. M. SPEIDEL.
